ATTORNEY.

UNITED STATES PATENT OFFICE.

FRANKLIN A. COLVER, OF FRANKFORT, INDIANA.

METALLIC FENCE-POST.

No. 928,108.

Specification of Letters Patent.

Patented July 13, 1909.

Application filed June 1, 1908. Serial No. 435,874.

To all whom it may concern:

Be it known that I, FRANKLIN A. COLVER, a citizen of the United States, residing at Frankfort, in the county of Clinton and State 5 of Indiana, have invented certain new and useful Improvements in Metallic Fence-Posts; and I do declare the following to be a full, clear, and exact description of the invention, reference being had to the accompanying drawings, and to the letters of reference marked thereon, which form a part of this 10 specification.

This invention relates to metallic posts that are designed more particularly for supporting wire fencing and which may be used also for supporting other types of fencing, such as that having horizontal wires and wooden pickets; the invention having reference particularly to the base parts of the 20 posts that are designed to be anchored securely in the ground and adapted to stand firmly.

The object of the invention is to provide a metallic fencing post that may be constructed of the minimum amount of material and at the same time have the maximum strength, so as to be constructed at relatively small cost and be durable and economical in use.

With the above mentioned and other objects in view, the invention consists in a post comprising a foundation or base part adapted to be embedded in the ground, and a standard part supported by the foundation part and formed either as an integral part 35 thereof or separately and secured removably thereto, and the invention consists further in a foundation part of novel construction; and further, the invention consists in the parts and combinations and arrangements of parts, 40 as hereinafter particularly described and defined in the following claims.

Referring to the drawings, Figure 1 is an elevation of the improved post having parts of the fencing wires connected thereto, as 45 when in use; Fig. 2, an elevation of the post as preferably constructed; Fig. 3, a fragmentary elevation on an enlarged scale showing one side of the post; Fig. 4, a fragmentary elevation showing another side of the post, 50 and particularly the lower portion of the foundation part; Fig. 5, a perspective view of a member of the foundation part; and Fig. 6, a lower end view of the foundation part.

Similar reference characters in the various 55 figures of the drawings indicate like parts or features of construction.

In the illustrations of a practical embodiment of the improvement *a* and *a'* indicate two feet for firmly supporting and anchoring the foundation part in the ground, the feet 60 being formed on an end of a body part *b* having spirally curved edges *c* and *c'*, the body part being composed of any suitable metal, such as cast-iron, but is preferably formed of rolled flat bar iron and twisted so as to have approximately the form of the body part of a boring auger, the feet *a* and *a'* being formed by splitting the end portion of the part longitudinally approximately at the middle of 65 its width and one part turned over in one direction and the other part turned over in the opposite direction, so that the feet extend laterally. The opposite or upper end of the foundation part has a relatively short straight part *d* in the middle of which is an 70 offset portion *e* forming one-half of a socket-wall. A companion member *f* is so shaped as to fit against the straight portion *b* and has a twisted portion *f'* adapted to the contour of the twisted portion of the body *b*, the 75 member having an offset portion *b'* forming the opposite wall of the socket. The member *f* is secured to the body or foundation part by means of rivets *g* and *g'* in the portion *f'* and bolts *h* and *h'* connecting the 80 main part *f* to the straight part *d*. The walls of the socket preferably have holes *i* therein to receive a bolt *j* whereby to fasten the standard part to the foundation part of the post, but is optional since the standard 85 part may be securely clamped by means of the bolts *h* and *h'* to the foundation part. The socket thus formed in the top of the foundation part may be obviously so shaped as to receive a standard part of any desired 90 shape which may be either rectangular in cross-section, or circular, since the standard part may be variously constructed and if desired might be formed of pipe or tubing.

The standard part of the post is preferably 100 removably attached to the foundation part as shown and preferably has a relatively strong thick lower portion *k* and a thinner and lighter weight upper portion *k'*, being tapered so that the lower portion has the 105 greater strength, and the whole length of the standard part has spirally curved edges as *l* and *l'*, and similar thinner edges *l''* at the upper portion. The lower portion of the standard is reinforced by a member *m* that 110 has the same contour as the body portion, being twisted, and is secured to the body por-

tion by rivets *n*. The standard has a suitable number of perforations *o* spaced at suitable distances apart throughout its length. The member *m* has perforations, and the 5 body portion of the standard obviously has similar perforations through which the bolt *j* may be passed. The lower end of the member *m* has a slightly twisted side to correspond with the twisted portions of the foundation parts that form the socket, the contour of the lower end of the body portion *k* conforming to the twisted portion, as will be 10 obvious.

In practical use suitable holes should be 15 dug in the ground and then the foundation parts of the posts may be placed in the holes with the upper portions thereof projecting slightly above the ground surface, and then the earth may be filled in and tamped in the 20 usual manner so that the feet *a* and *a'* will be firmly embedded in the ground, then fencing comprising wires *u* may be drawn through the apertures *o* and stretched to the corner posts in any suitable manner, or other kinds 25 may be suitably fastened on the posts as by means of wire loops extending through the apertures *o*, or other suitable fencing fasteners may be provided.

It will be readily seen that if preferred, the 30 entire post may be formed of one piece of twisted bar iron or steel, and also that the post may be galvanized to prevent corrosion or rusting thereof.

Having thus described the invention, what 35 is claimed as new, is:—

1. A post including a foundation part having a twisted body with spirally curved edges, the lower end of the part having a lateral foot thereon, the upper portion of the 40 part having one half of a socket formed thereof, and a companion member secured to the upper portion of the foundation part and forming the other half of the socket, with a standard part secured in the socket.

45 2. A post including a foundation part com-

prising a body that is oblong in section and twisted with spirally curved edges, the lower end of the part having lateral feet thereon, the upper portion of the part having one half of a socket formed thereof, a companion member having a twisted portion with spirally curved edges extending against the twisted body and forming the other half of the socket, devices securing the twisted portion of the companion member to the twisted 50 body, and means securing the upper end of the companion member to the upper end of the foundation part.

3. A post including a foundation part comprising a body that is oblong in section, 60 the body being twisted with spirally curved edges, one half of a socket formed of the upper portion of the part and formed partially of the twisted body, and a companion member that is twisted with spirally curved edges 65 and secured to the twisted body, the companion member forming the other half of the socket.

4. In a post, the combination of a foundation part having a twisted body with spirally 70 curved edges, the lower end of the part having lateral feet thereon, the upper portion of the part having one half of a socket formed thereof, a companion member having a twisted portion with spirally curved edges 75 and extending against the twisted body and forming the other half of the socket, devices securing the twisted portion of the companion member to the twisted body, and means securing the upper end of the companion 80 member adjustably to the upper end of the foundation part, with a standard part secured in the socket and held rigidly by said companion member.

In testimony whereof, I affix my signature 85 in presence of two witnesses.

FRANKLIN A. COLVER.
